His Attorney

UNITED STATES PATENT OFFICE

WILLIAM H. ROWE, OF CLIFTONDALE, MASSACHUSETTS, ASSIGNOR TO GENERAL ELECTRIC COMPANY, A CORPORATION OF NEW YORK

GLOBE HOLDER AND THE LIKE

Application filed July 20, 1931. Serial No. 551,824.

The present invention relates to holders, such as holders for attaching a lamp globe in position, although it is not limited to this use necessarily.

- 5 The object of the invention is to provide an improved globe holder which is simple in structure, reliable in operation, handy to use, and capable of being manufactured at low cost.
- 10 For a consideration of what I believe to be novel and my invention, attention is directed to the following description and the claims appended thereto.

In the drawing, Fig. 1 is a side view, partly 15 in section, of a globe holder embodying my invention, and Fig. 2 is a top view, partly in section.

Referring to the drawing, 1 indicates a stationary support, for example the upper 20 end of a lamp post upon which a lamp and globe are to be supported, and 2 indicates the globe.

Mounted on the upper end of post 1 is a supporting ring 3 which may be formed of 25 suitable metal and which is fixed in position on the post by a number of spaced screws 4. Ring 3 thus forms, in substance, a part of the stationary support of post. Projecting inwardly from the inner surface of ring 3 30 are a plurality of spaced ears 5 to which are fastened arms 6 which in turn support a lamp socket 7 which may be of any suitable construction. Projecting outwardly from the outer surface of ring 3 adjacent to its 35 upper edge are a plurality of circumferentially spaced ledges 8, three being shown in the present instance, to the under sides of which are attached spring latches 9 by means of screws 10. The latches may comprise 40 strips of spring metal bent outwardly to provide locking projections 11.

Attached to the globe 2 is a ring comprising a horizontal portion 12 upon which the lower end of the globe rests, a downwardly 45 projecting portion 13 which forms a flange surrounding ring 3, and an upwardly projecting portion 14 which extends up inside the globe and serves to center the globe. At spaced points around the upper edge of ring 50 portion 14 are inwardly projecting lugs 15 to

which are attached metal strips 16, the free ends of which engage the inner surface of the globe to hold it in place on ring portion 12. Strips 16 are attached to lugs 15 by bolts 17, and to hold the strips from turning, the tops 55 of the lugs are provided with recesses in which the ends of the strips are held by the bolts. This serves to provide a simple and efficient means for attaching the globe to the ring. Projecting inwardly from the lower 60 inner edge of globe ring portion 13 are a plurality of locking ledges or lugs 18 which engage with spring latches 9, lugs 18 being provided with shoulders 19 which engage with locking projections 11. Also projecting inwardly from the inner surface of ring portion 13 are spaced stop lugs 20 adapted to engage with the ends of ledges 8 to limit the 65 turning movement of the two rings relatively to each other in the locking direction. Lugs 70 18 project inwardly far enough so that they serve to center the two rings relatively to each other. The outer surface of globe ring portion 13 may be scalloped as shown at 21 to provide a grip for the hands. 75

In the use of the device the ring 3 is attached to the stationary support and the globe ring is attached to the globe in the ways already described. To lock the globe to the support the globe ring is placed over ring 3, 80 locking lugs 18 being to one side of ledges 8. The globe and globe ring are then turned on ring 3 to bring locking lugs 18 to positions in engagement with springs 9 as shown in the drawing, thus locking the globe in position. 85 Since locking lugs 18 fit under ledges 8, they serve to draw the parts together, thus seating the globe ring firmly on the supporting ring. To remove the globe, it is necessary only to turn the globe and globe ring to move lugs 90 18 from engagement with springs 9. It will thus be seen that the globe can be easily and quickly attached to and detached from the support. 90

The upper edge of ring 3 engages the under 95 surface of ring portion 12, thus making a connection which prevents bugs and insects from entering the globe.

In accordance with the provisions of the patent statutes, I have described the prin- 100

5 ciple of operation of my invention, together with the apparatus which I now consider to represent the best embodiment thereof; but I desire to have it understood that the apparatus shown is only illustrative and that the invention may be carried out by other means.

What I claim as new and desire to secure by Letters Patent of the United States is:

1. In a globe holder, the combination of a support comprising a supporting ring having spaced projecting ledges and spring catches carried by said ledges, a globe ring having a globe supporting portion and a portion concentric with said supporting ring, means for fastening a globe on said globe supporting portion, lugs carried by said concentric portion adapted to be brought into engagement with said spring catches by a turning movement of said globe ring, and stop means for limiting the turning movement of said globe ring.
2. In a globe holder, the combination of a supporting ring adapted to be fixed on a post, means carried by said ring for supporting a lamp socket, spaced ledges projecting from said ring, a globe ring having a globe supporting portion, a portion which rests on said supporting ring, and a portion concentric with said supporting ring, projecting ledges carried by said last named portion, and spring catches carried by certain of said ledges for clamping the rings together when the rings are turned relatively to each other to bring the ledges into alignment.
3. In a globe holder, the combination of a supporting ring adapted to be fixed on a post, spaced ledges projecting from said ring, a globe ring having a globe supporting portion and a portion which rests on said supporting ring, means carried by one of said rings for supporting a lamp socket, spaced projecting ledges on said globe ring adapted to be moved beneath the ledges on the supporting ring, and spring means for holding said ledges in locking engagement.

In witness whereof, I have hereunto set my hand.

WILLIAM H. ROWE.
